(57) **CLAIM**

The ornamental design for a magnetic building tile, as shown and described.

DESCRIPTION

FIG. 1 is a top perspective view of the magnetic building tile according to the invention;

FIG. 2 is a bottom perspective view of the magnetic building tile according to the invention;

FIG. 3 is a left view of the magnetic building tile according to the invention;

FIG. 4 is a right view of the magnetic building tile according to the invention;

FIG. 5 is a top view of the magnetic building tile according to the invention; and,

FIG. 6 is a bottom view of the magnetic building tile according to the invention.
